UNITED STATES PATENT OFFICE.

DAVID C. LARSON, OF YONKERS, NEW YORK, ASSIGNOR TO OTIS ELEVATOR COMPANY, OF JERSEY CITY, NEW JERSEY, A CORPORATION OF NEW JERSEY.

SWITCH-INTERLOCKING MECHANISM.

Application filed January 16, 1924. Serial No. 686,557.

To all whom it may concern:

Be it known that I, DAVID C. LARSON, a citizen of the United States, residing in Yonkers, in the county of Westchester and State of New York, have invented a new and useful Improvement in Switch-Interlocking Mechanism, of which the following is a specification.

My invention relates to interlocking means for switches and particularly to mechanical interlocks for magnet switches.

One object of my invention is to provide a mechanical interlock between two magnet switches whereby the simultaneous closing of two switches is prevented, and the closing of one switch prevents the closing of the second until the first switch has returned to its open position.

Another object of my invention is to provide a mechanical interlock between two or more magnet switches whereby the sequence of the closing and opening of these switches is definitely fixed, and more specifically, the opening sequence is required to be in the reverse order of the closing sequence.

Other objects will appear from the specification and claims.

My invention will be described by way of example in connection with two switches, as shown in the accompanying drawings in which:

Figure 1 is a plan view of two magnet switches in open position and illustrates an embodiment of my interlock for preventing the closing of either switch when the other is closed.

Figure 2 is an enlarged fragmental plan view of the interlock of Figure 1 with one switch in the closed position.

Figure 3 is a plan view of two magnet switches in open position and illustrates my interlock for establishing the sequence of closing and opening of the two switches.

Figure 4 is an enlarged fragmental plan view of the interlock of Figure 3 with both switches in the closed position.

Figure 5 is an elevation of the two switches and interlock shown in Figure 1 with one switch closed and the other open. Like numerals refer to like parts throughout the several views.

Referring to Figures 1, 2 and 5, magnet switches A and B are mounted on panel 1. These switches are adapted to be closed elec-

tromagnetically by energization of suitable coils and to be opened by the action of gravity upon de-energization of the coils. Switch A comprises magnet coil 2 and movable core 3 which is connected to switch arm 4 by rod 5 through pivot 35. Stationary contacts 6 and 7 are mounted on panel 1 and movable contacts 8 and 9 are mounted on switch arm 4. Lug 10 is provided on switch arm 4 to engage the interlock device. Similarly switch B is provided with a coil, core, and contacts, the stationary contacts 11 and 12 being mounted on panel 1 and the movable contacts 13 and 14 being mounted on switch arm 15, which is provided with lug 16 for engagement with the interlock device. The interlock device comprises support 17 attached to panel 1 between the two switches by bolt 18. Yoke 19 is pivotally mounted on pin 20 in support 17. Rod 21 is adjustably mounted in yoke 19 and held in place by nut 22. Interlock cam 23 is fastened to the end of rod 21 by pin 24. Cam 23 is provided with a V-shaped end having surfaces 25 and 26.

Assuming switches A and B open as shown in Figure 1, the energization of the coil 2 of switch A causes core 3 to be drawn within the coil 2, so that switch arm 4 moves around hinge pin 27 in switch arm support 28 to close contacts 6 and 8, and 7 and 9. Switch arm support 28 is secured to panel 1 by bolts 29. As the switch arm 4 moves, lug 10 on this arm strikes against surface 25 of cam 23, thereby pushing the cam 23 to one side around pin 20 as a center. Cam 23 and 25 the lugs 10 and 16 on switch arms 4 and 15 respectively are so positioned that lug 10 may pass entirely off the surface 25 of cam 23 before surface 26 of the cam strikes against lug 16 on arm 15 of switch B. It will be noted that with switch A closed, switch B is mechanically locked in the open position. This is due to the action of lug 10 in holding cam 23 stationary against movement by pressure of lug 16 on the inclined surface 26. When switch B is closed and switch A is open, the conditions are reversed from that shown in Figure 2, switch A being locked in the open position as long as switch B is closed. The motion of cam 23, rod 21 and yoke 19 is limited by either projection 28 or 29 on yoke 19 striking against either projection 30 or 31 on sup-

port 17, the object being to keep cam 23 from swinging about pivot 20 beyond a point at which it can be engaged by lugs 10 or 16.

5 The parts shown in Figures 3 and 4 are the same as those shown in Figures 1 and 2 with the exception of the interlock cam, which has means for preventing closing of the switches in any but a predetermined sequence, and means for preventing the opening of the switches in any but the reverse order of their closing. The cam 32 shown in Figures 3 and 4 is interposed in the path of movement of switch B and is provided 10 with an oblique surface 33 and slot 34. In this case switch A must be closed before switch B, as when both switches are open, lug 10 on arm 4 of switch A is interposed in the path of deflection of cam 32 and thus 15 prevents it from moving to permit switch B to close. After switch A has closed, switch B can then close, the lug 16 on arm 15 of switch B striking against surface 33 of cam 32, thereby pushing the cam toward 20 switch A so that lug 10 enters slot 34. When both switches are closed switch B must open first, as lug 10 on arm 4 is held in slot 34 as long as lug 16 is against the side of cam 32. Switch A is thus prevented from opening 25 until after switch B has opened. It will be noted that with the interlock shown in Figures 3 and 4, a definite sequence of operation of the switches is assured both in opening and closing, i. e., the one that closes first 30 must open last. Although I have shown but two switches in the drawing, it will be understood that my interlock may be applied to any number of switches to control the sequence of operation.

I claim:

1. Interlock mechanism for electromagnetic switches comprising in combination a pair of switch arms, and a locking cam interposed in the operating path of one of said arms but movable thereby into the operating path of the other arm to lock said other arm in position. 40
2. Interlock mechanism for electromagnetic switches comprising in combination a switch arm, a locking cam interposed in the operating path of said arm but deflectable thereby to permit said arm to operate, and a second switch arm normally interposed in the path of deflection of said locking cam but removed therefrom when operated. 45
3. Interlock mechanism for electromagnetic switches comprising in combination a switch, a locking cam interposed in the operating path of said switch but deflectable thereby to permit said switch to close, and a second switch preventing deflection of said locking cam when open but releasing the same when closed. 50
4. Interlock mechanism for electromagnetic switches comprising in combination a switch arm, a locking cam interposed in the operating path of said arm but deflectable thereby to permit said arm to operate, and a second switch arm normally interposed in the path of deflection of said locking cam but removed therefrom when operated, said locking cam having means to hold said normally interposed arm in its shifted position while said cam is deflected by the first mentioned switch arm. 55

In testimony whereof, I have signed my name to this specification.

DAVID C. LARSON.
